Inventor,

J. Wilkinson
By J. D. Fay, Atty.

UNITED STATES PATENT OFFICE.

JENNIE WILKINSON, OF CLEVELAND, OHIO.

GARMENT-SUPPORTER.

SPECIFICATION forming part of Letters Patent No. 733,102, dated July 7, 1903.

Application filed June 14, 1901. Serial No. 64,536. (No model.)

To all whom it may concern:

Be it known that I, JENNIE WILKINSON, a citizen of the United States, and a resident of Cleveland, county of Cuyahoga, and State of Ohio, have invented a new and useful Improvement in Garment-Supporters, of which the following is a specification, the principle of the invention being herein explained and the best mode in which I have contemplated applying that principle, so as to distinguish it from other inventions.

My invention relates to devices for supporting ladies' garments, its object being to render such device readily adjustable and also to prevent the tearing of the garments.

Said invention consists of means herein-after fully described.

Said device is particularly designed to support the skirt and simultaneously hold down the shirt-waist.

In devices of this class which have been in use it has been customary to employ a series of sharp teeth for catching the rear lower edge portion of the shirt-waist and hold same in place. Such arrangement has been found to be very objectionable in that it results in the tearing of the fabric of the shirt-waist. Such objectionable feature is eliminated by my said invention.

The annexed drawings and the following description set forth in detail certain mechanism embodying the invention, such disclosed means constituting but one of various mechanical forms in which the principle of the invention may be used.

In said annexed drawings, Figure 1 represents a perspective view of a garment-supporter embodying my invention. Fig. 2 is a rear elevation of the rear intermediate portion of my improved garment-supporter. Fig. 3 is a plan view of the portion shown in Fig. 2, and Figs. 4 and 5 illustrate the end portions of the two side pieces which are contiguous to the ends of the rear portion. Fig. 6 is a view showing a portion of a shirt-waist with the rear intermediate piece of the supporter in position thereon.

Said device consists of the rear intermediate piece A and the two side pieces B, all constructed of thin sheet metal. Piece A is provided upon its lower edge with a series of downwardly-projecting prongs a, which are

made blunt, so as to prevent all possibility of their catching and tearing fabric adjacent thereto.

As will be seen by referring to Fig. 6, the shirt-waist is provided with a series of braided loops c, through which the prongs a extend and are caught. This connection serves to hold the shirt-waist in position in an obvious manner.

Each end of piece A is provided with a slot a', and adjacent to each such slot is a series of keyhole-eyes a². Each contiguous end b of the side pieces B is reduced in size, so as to be capable of insertion through its respective slot a', and is provided with a button b', having a reduced neck and adapted to enter any one of the eyes a². In securing the side and rear pieces each of the former is passed through its respective slot a' from the outside inwardly and the button inserted and secured in one of the eyes a² contiguous to such end, as shown in Fig. 1.

The outer surface of each of the side pieces is provided with a series of hooks b², upon which the skirt is hung and supported, as is also the outer surface of the rear piece A, Fig. 2.

Suitable means are provided for securing the front ends of the two side pieces, such means, however, constituting no part of my herein-described invention.

The device as above described is simple in construction, may be readily adjusted to different lengths, the range of variation depending upon the number of eyes in the rear piece, as is readily understood, and presents no sharp points upon which the shirt-waist is liable to catch and tear.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention—

1. A garment-supporter comprising two side portions and a rear intermediate portion, the contiguous end of each side portion and rear portion being provided with a slot and a series of eyes and a button respectively, the

one portion passing through said slot and secured to the other by means of such button and one of said eyes, said intermediate portion being provided with a series of hooks and 5 downwardly-projecting blunt prongs.

2. A garment-supporter comprising two side portions and one rear intermediate portion, each such side portion being adjustably securable upon said rear portion, the latter

provided with a series of blunt teeth integral 10 therewith and projecting downwardly from the lower edge thereof.

Signed by me this 7th day of June, 1901:

JENNIE WILKINSON.

Attest:

D. T. DAVIES,
G. W. SAYWELL.
